UNITED STATES PATENT OFFICE.

CHARLES E. BARNES, OF NEW YORK, N. Y., ASSIGNOR OF ONE-HALF TO THEODORE G. STRATER, OF BROOKLINE, MASSACHUSETTS.

MULTIFORM CHAIR.

1,294,378.

Specification of Letters Patent. Patented Feb. 18, 1919.

Application filed April 18, 1918. Serial No. 229,230.

To all whom it may concern:

Be it known that I, CHARLES E. BARNES, a citizen of the United States, and resident of New York, county of New York, State of 5 New York, have invented an Improvement in Multiform Chairs, of which the following description, in connection with the accompanying drawing, is a specification, like characters on the drawing representing like 10 parts.

This invention relates to improvements in multiform chairs of the type disclosed in my prior application for Patent No. 169,665 filed May 19, 1917. The present device like 15 that disclosed in the preceding application comprises a chair having a rectangular, preferably square, frame provided with a seat pivotally secured to the frame and a back pivotally and adjustably secured to the 20 frame with means for adjusting the back from a substantially vertical position to a horizontal position in which it forms a continuation of the seat.

The chair also comprises a seat extension 25 with means for so supporting the same as to permit it to be inclosed within the frame beneath the seat when the device is to be used as a chair or to be withdrawn from its 30 inclosed position to form an extension lying in the plane of the seat when the device is to be used as a chaise longue or coach.

One of the objects of the present invention is to provide an improved means for adjustably securing the back to the frame 35 which will permit the adjustment of the back as aforesaid and when the back is in horizontal position to form an extension of the seat will retain the back firmly against the seat thereby avoiding any space which 40 otherwise might occur between the back and the seat, particularly if the chair should be drawn from place to place by pulling upon the horizontally positioned back.

Another object of the invention is to provide 45 a convenient means for assembling and knocking down the chair for packing and shipping. In the present invention the back is provided with means adapted telescopically to receive side members which are piv- 50 otally connected to the frame. The socket portions of such telescoping members are countersunk in the frame of the back so that the upholstering will overlie them while the other portions of the telescoping members 55 fit within the sockets and are secured thereto

by single screws which are hidden when the chair is assembled.

Another object of the invention is to provide means for so supporting the extension that the same may be supported in an inclined position as well as in a horizontal position in the plane of the seat. 60

Another feature of the invention consists in securing the arm portions of the chair to the frame by expandable dowel pins seated 65 in sockets, thereby retaining the arms firmly in position but permitting their easy removal when it is desired to place the arms transversely of the chair to transform the same into a settee. 70

Other objects and features of the invention will more fully appear from the following description, the accompanying drawings, and will be pointed out in the annexed 75 claims.

In the drawings:

Figure 1 is a view mainly in side elevation but partly in section showing in full lines my invention adapted to form a chaise longue and in dotted lines, various positions 80 illustrating the device prepared for other uses, 75

Fig. 2 is a side elevation of the same showing the device when assembled to form a settee, 85

Fig. 3 is a detail sectional view on lines 3-3, Fig. 1 of a portion of one of the sides of the back showing the position of the telescoping pieces by which the back is secured to the frame, 90

Fig. 4 is a vertical sectional view of the lower portion of the arm and the upper portion of the post showing the expandable dowel pin and socket for connecting the same together, 95

Fig. 5 is a detail elevation of a portion of the upper part of the sector,

Fig. 6 is a vertical sectional view of the mechanism for connecting the back, seat and frame, on line 6-6 Fig. 1, and, 100

Fig. 7 is a detail view showing a preferred means for supporting the front end of the seat extension when inclosed in the frame beneath the seat.

The device which is illustrated in the accompanying drawings comprises a chair having a frame consisting of vertical sides 1-2 and ends 3-4, the sides and ends being preferably mortised into the corner posts 5, 6, 7 and 8. The sides 1 and 2 are wider than 105 110

the ends 3, 4 and the upper surface of said sides lie flush with the top of the posts, whereas the top edges of the ends 3 and 4 lie below the tops of the posts at such distance as to be in the horizontal plane of the under surface of the back and seat extension when these members are in the extended position in which the device forms a couch.

The frame is rectangular in form, preferably square, so that the arms may be positioned either at the sides to form a "Morrison" chair or transversely of the device intermediate of its ends. The seat 9 which preferably is upholstered is of rectangular form to fit within the frame and rests at its forward edge upon the end piece 4. It is pivotally supported at its rear end upon the frame so that its front or free end may be raised to permit the extension to be inserted beneath it or withdrawn therefrom to form an extension of the seat when the device is to be used as a chaise longue or couch.

The back also preferably is pivotally connected to the frame by the same device as that which pivotally supports the seat so that both the seat and the back are adapted to be moved about the same pivotal axis. The preferred means for thus supporting the seat from the back comprises a pair of sector plates 11 which are secured to and preferably countersunk in the sides 1 and 2 of the frame adjacent the rear posts 5 and 7. These sectors desirably are in the skeleton form illustrated in Figs. 1 and 5 and are provided at their centers with journals to receive the pivots for the seat and the side members which support the back which will be hereinafter described.

The seat is pivotally supported by L-shaped brackets 12 which are attached to the bottom of the seat and have outwardly extending studs 14 which are seated in the journals of the sectors 11. The back 10 preferably is pivotally supported upon the same studs 14. A desirable means for mounting the back which is illustrated in the present drawing, comprises detachably telescoping members connected respectively to the sides of the back and to the frame. Each socket member 15, which is connected to the back, is formed of a flat piece of metal folded upon itself so as to present two parallel leaves 16, 17 having a space between them to receive the other member, one or both of said leaves being provided with lateral extensions 18, 19 which are countersunk in and secured to the edge of the frame of the back. The construction preferably is such that the upholstering of the back will entirely overlie these socket members. The other members of the telescoping side pieces comprise flat plates 20 which are provided intermediate their ends with offset portions 21 which bring the outer faces of the re-

maining portions 22 of said members flush with the outer walls of the socket members. This arrangement also provides a rigid support for the bottom of the socket members. The lower portions 22 of the flat plates are provided with slots 23 through which the pivots 14 extend so that the side pieces which support the back are pivotally and slidably mounted upon said pivot 14.

At their lower ends the members 22 of the side pieces are provided with laterally extending studs 24 which are adapted to engage the teeth 25 of the sector plates 11. The sector may be provided with any number of teeth to permit the adjustment of the back to desirable positions. The sector also desirably is provided with a guard 26 which is formed integral with it adapted to limit the movement of the stud 24 when the back is moved from one adjustment to another. The sector plates 11 are provided at their upper ends with upwardly extending reversely curved recesses 27, the curvature being such that when the back is lowered to horizontal position illustrated in dotted lines in Fig. 1 the studs 24 will ride upwardly in said recess and draw the inner end of the back firmly against the rear end of the seat. This is an essential feature of the present invention as it insures the closest union of the back and seat when the back is moved into horizontal position, thus avoiding an uncomfortable recess to a person lying upon the same. Furthermore, it prevents the separation of the back and seat if the device is drawn about the room by pulling upon the back after the device is extended.

The telescoping sections of the side pieces may be secured together by screws 28 which pass through the plates 16, 17 of the socket member and the intermediate member 20 of the side plate. By reason of the construction aforesaid the back can be removed from the assembled position illustrated in Fig. 1 for the purpose of packing the chair by merely withdrawing the screws 28 and raising the back upwardly until the socket members are disengaged from the inclosed plates 20. The back can then be laid upon the seat and secured in the usual manner. It will be noted that in this construction the lower sections 20 of the side plates do not extend above the level of the arms of the chair so that when the back is laid upon the seat for packing there will be no projections outside of the normal space occupied by the chair arms.

The device preferably is provided with a seat extension 29 which at its inner ends is supported upon a hinge plate, one leaf 30 of which is secured to the under surface of the frame of said extension while the other leaf 31 is of sufficient length to extend across the forward end piece 4 of the frame and is secured to a supporting member 32 which has

tenons 33 at its ends slidably mounted in guides 34 secured to the inner walls of the sides 1—2. These guides 34 desirably are of curved form and extend diagonally the 5 length of the sides 1 and 2, the curvature being such that when the supporting member 32 is in forward position (illustrated in Fig. 1) the upper surface thereof, and consequently the leaf 31 of the hinge, will be in 10 horizontal position.

By reason of this construction the seat extension 29 may be inserted in the space beneath the seat 9 and concealed from view. The seat extension and the back may each 15 be supported in horizontal position as illustrated in Figs. 1 and 2 by suitable legs pivotally secured within their outer ends. A desirable means comprises legs 35 which are supported upon pivots 36 in the frame of the 20 seat extension and back in such a manner that when the legs are folded they will lie within suitable recesses above the end pieces of said seat extension or back.

The legs 35 are provided at their upper 25 ends with pins 37 and 38 adapted to be engaged by spring plates 39 which are secured to cross pieces 40. The device preferably is provided with detachable arm sections 41, 42 each like those illustrated in my 30 application aforesaid which are adapted to be positioned either at the sides of the frame to form chair arms or transversely thereof when the device is in the form of a settee, to divide it into three seats. These 35 arms desirably are of skeleton form comprising end posts 44, 45 and side rails 46 and a top 47 connected by slats 48. The posts 44 and 45 extend downwardly below the side rail 46 sufficiently to permit said 40 rail to escape contact with the upholstered cushions of the device when the arms are placed transversely thereof. The posts 44, 45 desirably have at their lower ends dowel pins 49 slotted at their lower ends 50 and 45 expanded slightly, and the tops of the posts 5, 6, 7 and 8 are provided with sockets 51 lined with metallic bushings 52 to receive the ends of the dowel pins, as illustrated in detail in Fig. 4.

50 By reason of this construction the arms will be firmly held in place upon the insertion of the dowel pins into the sockets and can be readily removed when desired.

In order to prevent the front end of the 55 seat extension from dropping down, when inclosed within the frame beneath the seat, a strap 53 may be secured to the under surface of the forward end of the seat and detachably connected to a button 54 projecting downwardly from the under face of the front end of said extension. In order to provide for the easy insertion of the seat extension beneath the seat 9 I have provided a leg 55 which is pivotally mounted upon a 60 stud 56 upon the side of the seat, the lower

end of the leg having a laterally extending foot 58 adapted to rest upon the upper surface of the guide 34 so that when the seat is raised as illustrated in dotted lines in Fig. 1 it will support the same in the raised 70 position and permit the extension to be inserted or withdrawn. By reason of its pivotal connection however, this leg and foot may be turned to the position illustrated in full lines in Fig. 1 to permit the 75 seat to return to horizontal position.

It will be understood that the embodiment of the invention disclosed herein is illustrative and not restrictive and that various changes in construction, form and relation 80 of parts may be made within the spirit and scope of the following claims.

Having thus described my invention, what I claim as new and desire to secure by Letters Patent is:

85

1. A multiform chair comprising a frame having legs, a back, a movable seat, guiding means within said frame, a seat extension, supporting means for said seat extension carried by said guiding means and having 90 a pivotal connection with said guiding extension adapted to project beyond said frame whereby the outer end of said seat extension may be inclined downwardly.

2. A multiform chair comprising a frame 95 having legs, a back, a movable seat, guiding means within said frame, a seat extension, supporting means for said seat extension carried by said guiding means and having a pivotal connection with said guiding 100 extension adapted to project beyond said frame whereby the outer end of said seat extension may be inclined downwardly and a leg pivotally supported upon said seat extension adapted to hold the seat extension in 105 horizontal position.

3. A multiform chair comprising a frame having legs, a back, a seat pivoted at its rear end, curved guideways within said frame beneath said seat, a seat extension, supporting means for said seat extension slidably mounted in said guideway comprising a hinge connecting said supporting means to said extension, said hinge being adapted to rest upon said frame and to project beyond 110 the same to permit the outer end of said seat extension to be inclined downwardly.

4. In a chair comprising a frame having legs, a seat, a back and means for adjustably connecting said back to said frame including side members pivotally connected to said frame and extending upwardly along the sides of said back and brackets connected to the sides of said back and countersunk therein consisting of metallic plates 120 folded to embrace telescopically said side members and adapted to be covered by the upholstering of said back and means for locking said side members in said brackets.

5. A multiform chair comprising a frame 130

4

having legs, a pair of internally toothed sectors connected oppositely to the inner sides of said frame, coöperating pivotal means located at the centers of said sectors, 5 a back having side pieces pivotally and slidably mounted on said pivotal members and having means adapted adjustably to engage the teeth of said sectors whereby the position of said back may be adjusted and means for 10 preventing sliding movement of said side pieces when the back is in substantially horizontal position whereby separation of the back and seat will be prevented.

6. A multiform chair comprising a frame 15 having legs, a pair of internally toothed sectors connected oppositely to the inner sides of said frame, coöperating pivotal means located at the centers of said sectors, a back having side pieces pivotally and slidably 20 mounted on said pivotal members and having means adapted adjustably to engage the teeth of said sectors whereby the position of said back may be adjusted, said sectors being provided with an upwardly extending re- 25 versely curved restricted slot adapted to receive the means engaging the teeth of said sectors to prevent separation of said back and seat when the back is in substantially horizontal position.

Copies of this patent may be obtained for five cents each, by addressing the "Commissioner of Patents, Washington, D. C."

7. In a multiform chair comprising a frame having legs, a seat pivotally mounted at its rear end in said frame, an extension for said seat, guiding means within said frame for said extension adapted to permit said extension to be positioned beneath said seat and means foldably connected to said seat operable to hold the forward end of said seat in elevated position to permit said extension to be withdrawn and replaced.

8. In a multiform chair comprising a frame having legs, a seat pivotally mounted at its rear end on said frame, an extension for said seat, guideways in said frame, supporting means for said extension slidably mounted in said guideways adapted to permit the seat extension to be concealed beneath said seat or withdrawn beyond the forward end of said seat and members pivotally connected to said seat adapted when the front end of the seat is elevated to 40 rest upon said guideway and to sustain the forward end of said seat in elevated position and thereby to permit the withdrawal and replacement of said extension.

In testimony whereof, I have signed my 45 name to this specification.

CHARLES E. BARNES.
